UNITED STATES PATENT OFFICE.

THOMAS J. DIGNEY, OF BRIDGEPORT, CONNECTICUT.

SUBMARINE BARRIER.

1,271,864.

Specification of Letters Patent. Patented July 9, 1918.

Application filed August 13, 1917. Serial No. 185,979.

To all whom it may concern:

Be it known that I, THOMAS J. DIGNEY, a citizen of the United States, residing at Bridgeport, in the county of Fairfield and 5 State of Connecticut, have invented certain new and useful Improvements in Submarine Barriers, of which the following is a specification.

This invention relates to submarine mine 10 carrying barriers designed for protecting harbors, channels, and like bodies of water, and is particularly adapted for trapping submarine vessels and to form such entanglements that when engaged by the nose 15 or side of a submarine boat the latter will be positively prevented from escaping therefrom without contacting with or causing one or more of the mines carried by the barrier to be brought into engagement 20 with the vessel.

The invention consists of two upright beams or masts weighted at one end and having floats attached to their opposite ends, whereby to hold the beams or masts 25 in a substantially upright position, and to these vertically arranged beams or masts are projected horizontal arms or booms to which are connected steel nettings, and arranged between the said nets and connected 30 thereto and to the upright beams or masts is a net designed to obstruct the passage of a submarine vessel between the first-mentioned or horizontal nets. Suitable floats are connected to the upper horizontal net at 35 intervals throughout its length so as to hold the unit in position. The net also carries a plurality of contact mines so that when the unit is engaged by a submarine boat, the upright beams or masts will be drawn to- 40 ward each other and thus cause the mines to contact with the sides of the vessel. The invention further consists in certain novel and peculiar details of construction and arrangement of parts as will be hereinafter 45 fully described and then claimed.

In the drawings, illustrating the invention, in the several figures of which like parts are similarly designated, Figure 1 is a perspective view of my improved barrier. 50 Fig. 2 is a diagrammatic plan view of the same. Fig. 3 is a similar view illustrating the operation of the device. Fig. 4 is a fragmentary plan view of a submarine boat illustrating the contact of a protuberance 55 of a submarine boat with one of the ele-

ments of the barrier. Fig. 5 is a perspective view of a portion of one end of the barrier illustrating a slight modification.

1 designates beams or masts which may be 60 constructed of metal tubing or wood as desired, and throughout the description and claims I shall hereafter refer to these elements as "masts". The lower ends of the masts are provided with eyes 2 to which are connected cables or chains 3 of varying 65 length to hold the barrier at a predetermined distance below the surface of the water, regulated, of course, by the depth of the channel or waterway in which the barrier is located. The cables or chains 3 have their 70 lower ends connected to anchors 4 of sufficient weight to prevent dragging of the barrier through the influence of tides or currents. The upper ends of the masts 1 are 75 also provided with eyes 5 to which are connected chains or cables 6, having their upper ends connected to floats 7. It may be stated here that the floats are of sufficient 80 buoyancy to hold the masts in an upright position in still waters, and the cables or 85 chains 6 are of such a length as to hold the floats below the surface of the water so that the floats will not be detected by hostile surface vessels entering or passing through the protected harbor or channel in which my improvement is installed.

To the masts 1 are connected arms or 90 booms 8, extending at right angles from the said masts, and hence in a substantially horizontal position, and to these arms or 95 booms 8 are connected wire nettings 9, as shown most clearly in Fig. 1. To the longitudinal edges of the upper nettings 9, and to the center thereof, are connected a plurality of floats 10 which serve to hold the 95 said nets in a horizontal position. Connected to the masts 1 and to the upper and lower nets 9 is a wire net 11, which serves to prevent passage through the barrier as will be best understood from the general 100 description of the device. Extending outwardly from the masts 1 are arms 12 having their outer ends terminating in eyes 13 to which are connected cables or chains 14 105 supporting contact mines 15. The arms 12 are braced by stay lines 16 extending from suitable points from the arms and connected to the outer ends of the booms 8.

In order to hold the masts in a substantially vertical position and to prevent ex- 110

cessive inclination of the barrier, owing to swift currents or tides, the said masts have their upper ends connected by cables 17 extending outwardly and in diverging directions from the upper ends of the masts 1 and having their lower ends connected to anchors 18.

As shown in dotted lines in Fig. 1, I may provide contact mines 20 at the outer ends 10 of the booms, the said mines 20 being supported by cables 21 in a manner similar as that described with respect to the mines 15.

In practice the barriers are, as is customary with other devices for protecting harbors or channels, laid transversely of the channel, and I purpose to so space my improved barrier so that the contact mines 15 will be positioned near enough to each other to prevent the passage of a submarine vessel 20 between them without avoiding contacting either one or the other of the said mines. This arrangement, of course, is followed out when the barriers are positioned in alignment across the channel.

25 I show in Fig. 2, a diagrammatic plan view of the barrier with the prow of a submarine boat S approaching the center of the net. Now as the boat strikes the wire netting 11 it will drag the anchors 4 and 18 so as to draw the masts 1 toward each other, as shown in Fig. 3, thus causing the mines 15 to engage the sides of the boat, it being understood that the netting will readily bend and lend itself to the position shown in 30 Fig. 3. In the event of the employment of the mines 20, it will be understood that they will first strike the sides of the vessel and hence cause its destruction. Now in the event of the commander of the submarine boat 40 detecting the obstruction, and attempting to descend or to rise to avoid the obstruction, the bottom or deck of the bow of the boat, as the case may be, will strike either the lower or upper net 9, and thereby cause the 45 masts 1 to be drawn toward each other so as to permit one or the other of the mines 15 or 20 to come in contact with the boat. On the other hand, should the commander of the vessel seek to "back out" and to shift his 50 course, either to the right or to the left, the vessel will be brought into contact with either of the mines 15 or 20. In this connection, I might say that I may provide the 55 ends of the barrier with nets 22, as shown in Fig. 5, so as to obstruct the passage of the boat around the ends of the barrier should the obstruction be detected before the vessel has made such progress as to drag the anchors sufficiently to cause the contact mines 15 or 20 to be brought into contact with the sides of the boat.

60 In practice the nets may be of varying length and height, as well as breadth, as will be well understood, and should the channel-way or harbor be of exceptional depth, the

barrier will consequently be made deeper, and a plurality of contact mines 15 or 20, other than shown, may be employed instead of the single mines at the ends of the barrier.

65 In the event of the conning tower or periscope of a submarine boat coming into contact with either one of the arms or booms 8, it will be appreciated that the arm will be turned, so to speak, with the mast 1 acting as a pivot, to thus throw the contact mines 15 or 20 in contact with the sides of the boat. This feature is illustrated in Fig. 4 of the drawings.

70 Should a surface vessel ride over and contact with the upper net 9 of the barrier, the central portion thereof will be forced downwardly through the weight of the vessel to thus cause one or the other of the contact mines to strike against the side of the vessel. In this connection, I might say that in practice I may supplant some of the buoyant floats 10 with floating contact mines, which are anchored to the net in the same manner as the floats, which will thus serve the double purpose of floats and mines whereby to insure the destruction of the boat as it comes 75 into contact with the barrier.

80 It will thus be seen that I provide an improved form of net that forms a trap whereby to positively avoid escape should a hostile 85 vessel come into contact therewith.

85 It will be appreciated, that in the drawings, I have illustrated my apparatus as being installed in a channel at ebb tide wherein the floats and various parts of the barrier 90 will assume a substantially vertical position, and it will, of course, be understood that during the flow of the tide, the floats will naturally be deflected from the vertical line of their anchorage. However, by the employment of the cables 17 I seek to maintain the masts 1 in a substantially vertical position, and, at least, to prevent such inclinations thereof and of the barrier as to always 95 maintain them in an effective position.

100 It will be well understood that while I have described the nets of my barrier as being constructed preferably of steel, that they may be made of rope, chains, or the combination of steel, rope, or chains, and I therefore 105 do not wish myself to be limited to any special material or to any special construction of the nets.

110 What I claim is:—

1. A submarine barrier, comprising masts, 115 a vertically disposed net connected to said masts, horizontally disposed nets connected to the upper and lower edges of said vertical net, floats carried by said nets, and mines carried by said barrier.

120 2. A submarine barrier, comprising masts having booms extending therefrom adjacent to their upper and lower ends, a net connected to said masts, horizontally disposed nets connected to said booms and to said 125

first-mentioned net, floats carried by said upper horizontally arranged nets, and contact mines carried by said barrier.

3. A submarine barrier, comprising masts having booms extending therefrom adjacent to their upper and lower ends, a net connected to said masts, nets connected to said booms and to said first-mentioned net whereby to form a trap, floats connected to said barrier for maintaining the same in a substantially vertical position, and contact mines carried by said barrier, substantially as and for the purpose specified.

4. A submarine barrier, comprising masts having booms extending therefrom adjacent to their upper and lower ends, nets connected to said booms, a net connected to said masts and to said booms providing a trap, substantially as and for the purpose specified, mines carried by said barrier, and anchoring cables connected to said masts.

5. A submarine barrier, comprising masts, a vertically arranged net connected to said masts, horizontally disposed nets connected to the upper and lower edges of said vertically arranged net, floats connected to the upper of said horizontally disposed nets, anchors connected to said barrier whereby to maintain it in position, and mines carried by said barrier.

6. A submarine barrier, comprising masts having booms extending therefrom adjacent to their upper and lower ends, a net connected to said masts, nets connected to said booms and to said first-mentioned net, anchors connected to the lower ends of said masts, floats connected to the upper ends of said masts, and contact mines carried by said barrier.

7. A submarine barrier, comprising masts having booms extending therefrom adjacent to their upper and lower ends, a net connected to said masts, nets connected to said booms and to said first-mentioned net whereby to form a trap, substantially as specified, anchors connected to the lower ends of said masts, floats connected to the upper ends of said masts, whereby, in combination with said anchors, to maintain said barrier in a substantially upright position, and contact mines carried by said barrier.

8. A submarine barrier, comprising masts having booms extending therefrom adjacent

to their upper and lower ends, nets carried by said masts and said booms, means for maintaining said barrier in a substantially upright position, and contact mines carried by said barrier.

9. A submarine barrier, comprising masts having booms adjacent to their upper and lower ends, anchors connected to the lower ends of said masts, floats connected to the upper ends of said masts, a net connected to said masts, nets connected to the upper and lower ends of said first-mentioned net, and mines carried by said barrier.

10. A submarine barrier, comprising masts having booms adjacent to their upper and lower ends, anchors connected to the lower ends of said masts, floats connected to the upper ends of said masts, a net connected to said masts, nets connected to said booms and to said first-mentioned net, arms extending from said masts, and mines carried by and at the outer ends of said arms.

11. A submarine barrier, comprising masts having booms adjacent to their upper and lower ends, anchors connected to the lower ends of said masts, floats connected to the upper ends of said masts, a net connected to said masts, nets connected to said booms and to said first-mentioned net, arms extending from said masts, mines carried by and at the outer ends of said arms, and stay lines connected to the upper ends of said masts whereby to hold them in a substantially vertical position.

12. A submarine barrier, comprising masts having booms extending therefrom adjacent to their upper and lower ends, anchors connected to the lower ends of said masts, and floats connected to the upper ends thereof, a net connected to said masts, nets connected to said booms and to the upper and lower ends of said first-mentioned net, floats supporting the upper one of said second-mentioned nets, mines carried by said barrier, and anchor cables connected to the upper ends of said masts, substantially as and for the purpose specified.

In testimony whereof I have hereunto set my hand this 9th day of August, A. D. 1917.

THOMAS J. DIGNEY.
